UNITED STATES PATENT OFFICE.

JUDSON BUCHANAN, OF CHATTANOOGA, TENNESSEE.

CANE-MILL.

1,309,015.

Specification of Letters Patent.

Patented July 8, 1919.

Application filed October 31, 1916. Serial No. 128,702.

To all whom it may concern:

Be it known that I, JUDSON BUCHANAN, a citizen of the United States, residing at Chattanooga, in the county of Hamilton and 5 State of Tennessee, have invented a new and useful Improvement in Cane-Mills, of which the following is a specification, reference being had to the accompanying drawing.

My improvement relates particularly to 10 cane mills comprising a plurality of metal rolls between which the stalks of cane are passed under such compression as will expel the juices from the tissues of said stalks.

The object of this invention is to so modify 15 said rolls as to produce more effective action between rolls in grasping the cane stalks and drawing them forward between the rolls. This result is attained by modifying the contour of one of said rolls, as will be herein- 20 after described.

In the accompanying drawings,

Figure 1 is a perspective view of a cane mill embodying my improvement;

Fig. 2 is a sectional elevation of said mill;

Fig. 3 is a horizontal section on the line, 3—3, of Fig. 2;

Fig. 4 is a section on the line, 4—4, of Fig. 2;

Fig. 5 is a section on the line, 5—5, of 30 Fig. 2;

Fig. 6 is a view of one of the rolls de- 35 tached from the mill, a portion of another roll being adjacent;

Fig. 7 is a section on the line, 7—7, of 40 Fig. 6.

Referring to said drawings, A is a base plate; B is a top plate, and C, C, are side plates resting on the base plate and supporting the top plate. Upright bolts, D, D, bind 45 said plates together to form a frame within which the rolls are located.

The base plate has a bearing, A¹, and the top plate has a bearing, A². Said bearings receive the ends of the axle, E¹, of the large or primary roll, E, which is located between the plates, A and B. The upper end of the axle, E¹, has a cross head, E², to which power is applied for rotating said axle and the roll, E. In the base plate, A, is another bearing, A², and in the top plate, B, is another bearing, B². Said bearings receive the journals, F¹, of a smaller or secondary roll, F, which is so located as to bear against the perimeter of the primary roll, E. In said 50 bearings are follower blocks, F², and bolts, F³, extend horizontally through the walls of

said bearings and are adapted to be driven forward to move said followers for moving the roll, F, toward the primary roll, E. In said base plate is another bearing, A³, and in 60 the top plate, B, is another bearing, B³, located above the bearing, A³. Said bearings receive the journals, G¹, of a secondary roll, G, which is so located as to bear against the perimeter of the primary roll, E. In said 65 bearings are follower blocks, G², and bolts, G³, extend horizontally through the walls of said bearings and are adapted to be driven forward to move said followers for moving the roll, G, toward the primary roll, E. A 70 mouth plate, H, is placed on the outside of the mill and in front of the "pass" or passage between the rolls, E and G. Said plate is secured to the top plate, B, by means of a bolt, H¹.

On the roll, E, is a gear wheel, E⁴, meshing with a smaller gear wheel, F⁴, on the roll, F, and with a gear wheel, G⁴, on the roll, G.

The mill as thus far described has heretofore been known. But it remains to describe the particular form of the roll, G, and its relation to the other rolls and the operation of the three rolls in consequence of the particular form of the roll, G.

While the rolls, E and F, are merely roughened with a view to facilitating engagement with the cane stalks, the roll, G, has relatively deep and wide transverse grooves, G⁴, extending around the roll. In 90 the form shown in the drawings, the cross section of each of said grooves presents a curve formed on a center located outside of the perimeter of the roll. In practice, I have formed this roll with a continuous perimeter and with the same diameter as the roll, F, and then cut the grooves, G⁴, one inch wide with un-cut faces, G⁵, one-half inch wide between them and between the upper and lower grooves and the adjacent 95 ends of the roll. The surface in each groove should be roughened. I have transversely channeled each groove, G⁴, to form small ribs, g⁴, similar to screw threads on a small worm gear wheel (see Figs. 6 and 7). This 100 construction of the roll, G, thereby facilitates the feeding of the cane stalks into the mill, and slipping and failure of the stalks to promptly enter the pass between this roll and the roll, E, are overcome. Large stalks 110 as well as small ones are promptly and forcefully drawn into the pass. Stalks of sizes

which have heretofore made feeding difficult are easily drawn in. Furthermore, the crushing of the stalks and the expressing of the juices are effectively done. In the pass 5 between the roll, E, and the roll, G, the stalks are broken and partially flattened and are prepared for final compression in the pass between the rolls, E and F, which have continuous surfaces adapted for such final 10 compression.

It is to be observed that the grooves, G⁴, are not deep enough to allow the passing of a cane stalk without crushing. Every stalk 15 will have its walls broken, yet the pass is large enough at each groove to permit grasping of the stalk. In other words, the cross-sectional area of the grooves, G⁴, must be less than the cross-sectional area of the cane 20 stalks.

It must also be observed that the small 25 ribs, g⁴, assist in effecting engagement of the stalks in the grooves, G⁴. Furthermore, it must be noted that the curvature of the surface in the grooves, G⁴, extends the area of contact with the cane stalk. When a cane 30 stalk is too large to lie entirely in one of the grooves, G⁴, a portion of the crushed stalk will extend upward over the adjacent face, G⁵, and another portion extends downward over the adjacent face, G⁵. Thus the 35 engagement between the rolls and the stalk is still further extended. This last observation leads to the further fact, that if both rolls had continuous faces, they would present parallel lines between which the cane 40 stalks must pass. In so passing, each flattened stalk would present a greater mass of material at its middle than at its edges. Hence the engagement of the stalk would be 45 much stronger, if not exclusive, at its middle, the parts at each side of the middle being only slightly or not at all engaged. In other words, the engagement would be over a limited area. By the use of the 50 groove, G⁴, the middle part of the stalk is amply engaged and at the same time each edge of the flattened stalk is also vigorously engaged. Thus there is a large area of engagement.

Another characteristic of my improved 55 mill is derived from the grooves, G⁴. The axes of the rolls, F and G, may be spaced equi-distant from the axis of the roll, E, and the gear wheel, F⁴, on the roll, F, and the gear wheel, G⁶, on the roll, G, may be 60 of equal size and have equal numbers of teeth, and yet the roll, F, will tend to pass the material faster than the roll, G, tends to pass the material. In other words, in the 65 second pass—the pass between the rolls, E and F, there will be "drawing." This is a function which is desirable for the sake of avoiding clogging or choking of the material between the two passes. This "drawing," 70 although the two smaller rolls are equally

geared with the larger roll and equally spaced therefrom, is due to the presence of the grooves, G⁴, in the roll, G, these grooves bringing the major portion of the engagement of the cane stalks in this pass nearer 75 the axis of the roll, G, whereby the surface velocity at the dominating portions of said engagement is made less than such velocity in the second pass. Heretofore it has been sought by some manufacturers to differentiate 80 the gear velocity of the two smaller rolls of such mills in order to produce greater velocity in the second pass.

I claim as my invention,

1. In a cane mill, the combination of 85 three rolls, one being a primary roll and the other two being secondary rolls, the primary roll having a longitudinally continuous face and being set in opposition to the secondary rolls to form two passes, and 90 the secondary roll at the intake side of the mill having transverse grooves separated from each other by relatively narrow spaces and having a depth less than their width and their width being approximately equal to the 95 diameter of the cane stalks which are to be crushed, substantially as described.

2. In a cane mill, the combination of 100 three rolls, one being a primary roll and the other two being secondary rolls, the primary roll having a longitudinally continuous 105 face and being set in opposition to the secondary rolls to form two passes, and the secondary roll at the in-take side of the mill having transverse grooves and relatively narrow un-cut faces between said grooves, said grooves having a depth less than their width and their width being approximately equal to the 110 diameter of the cane stalks which are to be cut, substantially as described.

3. In a cane mill, the combination of three 115 rolls, one being a primary roll and the other two being secondary rolls, the primary roll having a longitudinally continuous 120 face and being set in opposition to the secondary rolls to form two passes, and the secondary roll at the in-take side of the mill having transverse grooves separated from each other by relatively narrow faces and having a depth less than their width 115 and their width being approximately equal to the diameter of the cane stalks which are to be crushed, and the surfaces in said 125 grooves being roughened, substantially as described.

4. In a cane mill, the combination of three 130 rolls, one being a primary roll and the other two being secondary rolls, the primary roll having a longitudinally continuous face and being set in opposition to the secondary rolls to form two passes, and the secondary roll at the in-take side of the mill having transverse grooves and relatively narrow uncut faces between said grooves, and said grooves having a depth less than their width and 135

their width being approximately equal to the diameter of the cane stalks which are to be crushed, and the surfaces in said grooves being roughened, substantially as described.

- 5 5. In a cane mill, the combination of three rolls, one being a primary roll and the other two being secondary rolls, the primary roll having a longitudinally continuous face and being set in opposition to the secondary roll at the in-take side of the mill having transverse grooves and relatively narrow un-cut faces between said grooves, said grooves having a depth less than their width and their width being approximately equal to the diameter of the cane stalks which are to be crushed, and the surfaces in the grooves being transversely ribbed, substantially as described.
- 10 10. In a cane mill, the combination of three rolls, one being a primary roll and the other two being secondary rolls, the primary roll having a longitudinally continuous face and being set in opposition to the secondary rolls to form two passes, and the secondary roll at the in-take side of the mill having transverse grooves separated from each other by relatively narrow faces and having a depth less than their width and their width being approximately equal to the diameter of the cane stalks which are to be crushed, and the surfaces in the grooves being transversely ribbed, substantially as described.
- 15 15. In a cane mill, the combination of three

rolls, one being a primary roll and the other two being secondary rolls, the primary roll having a longitudinally continuous face and being set in opposition to the secondary roll at the in-take side of the mill having transverse grooves and relatively narrow un-cut faces between said grooves, said grooves having a depth less than their width and their width being approximately equal to the diameter of the cane stalks which are to be crushed, and the surfaces in the grooves being transversely ribbed, substantially as described.

In testimony whereof I have signed my name, in presence of two witnesses, this 17th day of October, in the year one thousand nine hundred and sixteen.

JUDSON BUCHANAN.
